ADJUSTABLE LIGHT HOLDER.

John F. Warywoda, 328 SE. Thornton, Des Moines, Iowa

Filed Sept. 12, 1960, Ser. No. 62,123

Term of patent 14 years

(Cl. D48—4)

FIG. 2

Fig. 1 is a perspective view of an adjustable light holder, showing my new design, with a light bulb shown in broken lines for illustrative purposes only and the cord shown broken away in part to indicate indeterminate length.

Fig. 2 is a perspective view thereof from the opposite side of Fig. 1 with the bulb omitted.

I claim:

The ornamental design for an adjustable light holder, as shown and described.
